UNITED STATES PATENT OFFICE.

HENRY HERMANI, OF BALTIMORE, MARYLAND, ASSIGNOR TO THE TIN DECORATING COMPANY, OF BALTIMORE, OF BALTIMORE, MARYLAND, A CORPORATION OF NEW JERSEY.

LOOSE COVER AND CUTTER FOR HERMETICALLY-SEALED TINS.

Application filed July 14, 1922. Serial No. 574,924.

To all whom it may concern:

Be it known that I, HENRY HERMANI, a citizen of the United States, and resident of Baltimore and State of Maryland, have invented certain new and useful Improvements in Loose Covers and Cutters for Hermetically-Sealed Tins, of which the following is a specification.

This invention relates to a can opening device, and more particularly to an opening or cutting device for hermetically sealed metal cans of the tagger-tin type provided with a supplemental cover; and has special reference to the provision of an improved supplemental cover and cutter device for such cans or tins.

The principal object of the present invention comprehends the provision of an improved supplemental cover and cutter of the type now widely employed in packaging food, tobacco and other products in which a flanged loose or supplemental cover is provided adjacent its periphery with a loose and radially movable cutter device normally lying in an inoperative position between the cover flange and the body of the can, and movable to an operative position for puncturing and cutting away the tagger-tin top when the cover is forced downwardly and rotated on the can. In the use of these supplemental covers and cutters, difficulty is oftentimes experienced in rotating the covers on the cans, especially when the cover fits relatively tightly on the can, the grasping of the cover by the hand for rotating the same accentuating or aggravating the difficulty by reason of the fact that the pressure on the top wall and side wall or flange of the cover exerted by the hand increases the friction between the walls of the cover and the body walls of the can. Moreover, where the can is made of relatively large dimensions, increased difficulty is experienced in rotating the cover which is correspondingly of large radius. To overcome these disadvantages, the present invention comprehends a construction in which the cover may be rotated without increasing the friction between the parts, rotation of the cover being attended without unduly pressing the top wall and without forcing or exerting pressure on the flange of the cover, and in which rotation of covers of relatively large radii may be efficiently facilitated.

In the employment of these supplemental covers and cutters, in order to remove any liability of producing an accidental puncture or perforating of the sealed tagger-tin top, before placing the supplemental cover on the can in the packaging operation the loosely slideable cutter thereon must be located in its inoperative position so as to lie between the can body and the cover flange. The cutter in being loosely slideable on the cover oft-times moves or migrates to its operative or cutting position, this occurring usually when the cover is tampered with or handled during shipping or storage use, and when the covers are forced as during stacking of the cans, the sealed tops are punctured with the result that the seals of the cans are destroyed. By my present invention, this danger or liability is successfully obviated and the cutters when once placed by the packer in an inoperative position are held in such position until they are moved into cutting position when opening of the can is desired.

The principal objects of the present invention may be said to include, besides the provision of an improved supplemental cover and cutter having the characteristics above referred to, the further provision of a cover and cutter of this nature in which the cover is provided with a handle movable from an inoperative position to an operative position with the handle extending beyond the periphery of the cover and adapted to be grasped by the hand of the operator for rotating the cover, pressure of the hand being released from the cover parts and opening of large sized cans being facilitated; the further provision of a device of this nature in which the handle is mounted on the cover for slideable movement thereon from an inoperative position lying within the confines of the cover to its operative position extending beyond the cover; the still further provision of a device of this nature in which the handle is constructed to normally bear upon the cutter device so as to retain the same in its inoperative position to prevent accidental perforating or puncturing of the sealed tops; and the still further provision of a supplemental cover, cutter and handle made of relatively few parts and constructed to perform the desired functions in a highly desirable manner.

To the accomplishment of the foregoing and such other objects as may hereinafter appear my invention consists in the elements and their relation one to the other, as hereinafter particularly described and sought to be defined in the claims, reference being had to the accompanying drawings which show a preferred embodiment of the invention, in which:

10 Fig. 1 is an enlarged fragmentary view of the can and supplemental cover and handle therefor, with parts shown in section;

15 Fig. 2 is a plan view thereof showing the cover handle in its inoperative position;

Fig. 3 is a plan view of the same showing the handle in extended or operative position ready to be grasped for rotating the cover;

20 Fig. 4 is a view in cross-section taken on the line 4—4, Fig. 1; and

Fig. 5 is a fragmentary view with parts in cross-section showing the parts ready for effecting the cutting operation.

25 Referring to the drawings, I show the can or tin 10 provided with the tagger-tin top 11 sealed thereon in the usual manner, the said tagger-tin top being preferably provided with the annular cutting groove or depression 12. The can 10 is provided with the loose or supplemental cover 13, the said cover carrying a cutting device *c*. The cutting device *c* is loosely and radially movable in the slot 14 on the supplemental cover 13, the said cutting device being provided with the triangular shaped down-turned blade portion 15, and being further provided with opposed wing or tongue portions 16 extending through the slot 14 of the cover and being turned downwardly to engage the top wall or surface of the cover, the said wings 16 cooperating with the slot 14 for guiding the movement of the cutter from an inoperative position shown in Figs. 1 and 2 of the drawings with the blade 15 lying between the flange 17 of the supplemental cover and the side walls 10 of the can to an operative position as shown in Figs. 3 and 5 of the drawings with the blade 15 received by the annular groove 12 for perforating and cutting the sealed top 11.

As heretofore mentioned, a principal object of the present invention comprehends the provision of a construction in which rotation of the supplemental cover 13 may be effectively facilitated, especially when the cover tightly fits the can body, and in which rotation of covers of relatively large radii may be accomplished with facility and ease.

60 To these ends, I provide the supplemental cover 13 with a handle movable from an inoperative position to an operative position whereby the handle may be grasped by the operator and moved to effect rotation of the cover. In the preferred construction, I pro-

vide a slidably movable handle 18 carried by the cover and slidably movable thereon from a position shown in Figs. 1 and 2 of the drawings, with the handle lying within the confines of the can body to a position shown in Figs. 3 and 5 of the drawings, with a portion of the handle extending beyond the periphery of the cover ready to be grasped for rotation of the cover to break the can seal. The handle 18 may be made from a single blank of sheet metal formed into the configuration clearly shown in the drawings, the spaced side edges 19 of the handle being preferably inturned as shown for example in Figs. 2 and 4 of the drawings, a strong and reinforced sheet metal handle being thereby provided. For slidably supporting the handle on the cover, the said cover 13 is preferably provided with the spaced strap portions 20 and 21 formed preferably integrally with the cover, each of the said strap portions being provided by producing parallel slits in the cover and striking the strap portion up from the cover, as will be clear from a consideration of the drawings. The strap portions 20 and 21 are preferably spaced in the manner indicated with one of the strap portions, such as 20, centrally located and the other strap portion 21 arranged adjacent the periphery of the cover, this to the end of providing means for effectively taking up the strains during can opening operation with the proper leverage obtained for the handle. The handle 18 at its rear end may also be provided with the upturned flap or tongue 22, this tongue functioning as a stop member and cooperating with the strap portion 20 for limiting the outward movement of the handle 18 as clearly shown in Fig. 3 of the drawings.

105 For the purpose of retaining the cutter *c* in its inoperative position with the cutting member or blade 15 seated between the flange of the cover and the body walls of the can, this in order to obviate accidental puncturing of the tagger-tin top, the handle 18 is mounted on the cover so as to normally overlie the cutter *c*, the construction furthermore being such that the handle 18 normally bears upon the cutter *c* to retain the same in fixed inoperative position. A convenient and simple construction to effect this result is exemplified in the drawings, the handle 18 being provided at its front end with a single ply tongue portion 23 normally resiliently bearing against the cutter *c* as clearly shown in Fig. 1 of the drawings to retain the same in inoperative position as indicated in said figure. To provide the tongue 23, the inturned side portions or flaps 19 of the handle 18 may be made to terminate short of the front end of the handle as indicated at 24 in the drawings.

110 115 120 125 130 The manner of making and using my improved can opening device will in the main

be fully apparent from the above detailed description thereof. In placing the loose or supplemental cover on the can body the cutter *c* is put or placed in its inoperative position with the front tongue portion 23 of the handle exerting pressure thereon to retain the same in such position so that upon mounting the supplemental cover on the can the cutting blade of the cutter will be positioned between the flange of the cover and the walls of the can body. For rotating the cover to open the can, the cutting device is moved to its inner or cutting position and the handle 18 is moved outwardly to a position shown in Fig. 3 of the drawings, so that the front portion of the handle may be grasped by the hand of the operator to effect rotation of the cover. In opening a small sized can, by exerting the pull on the handle 18 undue pressure is released from the cover top and flange portions, rotation of the cover being thereby facilitated. Where a relatively large sized can is to be opened, the can body may be taken hold of by one hand of the operator and the cover rotated by grasping the handle with the other hand and exerting a pull thereon. By arranging the handle 18 in a position overlying the cutter *c*, I am not only enabled to retain the cutter in inoperative position when desired, but I am enabled to exert the effective pressure, in opening the can, on the cover portion in which the cutter is mounted, the cutter being thereby forced home throughout the full cutting operation.

While I have shown my device in the preferred form, it will be obvious that many changes and modifications may be made in the structure disclosed without departing from the spirit of the invention, defined in the following claims.

I claim:—

1. In combination, a loose or supplemental cover for hermetically sealed tins or cans, a cutter carried by the cover for removing or cutting away the sealed or tagger-tin top of the can when the cover is rotated on the same, and a handle carried by the cover normally lying in an inoperative position within the confines of the cover and movable from such position to an operative position with the handle extending beyond the periphery of the cover for being grasped to rotate the same.

2. In combination, a loose or supplemental cover for hermetically sealed tins or cans, a cutter loosely carried by the cover and radially movable thereon from an inoperative position to an operative position for removing or cutting away the sealed tagger-tin top of the can when the cover is rotated on the same, the handle carried by the cover movable from an inoperative position within the confines of the cover to an operative position with the handle extending or project-

ing from the periphery of the cover to be grasped for rotating the same, the said handle being made out of sheet metal provided with lateral inturned edges and having its end formed into a tongue member 70 normally overlying the cutter and bearing upon the same to hold the same in its inoperative position against accidental displacement.

3. In combination, a loose or supplemental cover for hermetically sealed tins or cans, a cutter carried by the cover for removing or cutting away the sealed or tagger-tin top of the can when the cover is rotated on the same, and a handle carried by the cover and 80 slidably movable thereon from an inoperative position within the confines of the same to an operative position with the handle extending beyond the periphery of the cover for being grasped to rotate the same. 85

4. In combination, a flanged or supplemental cover for hermetically sealed tins or cans, a cutter loosely carried by the cover and radially movable thereon from an inoperative position between the flange of the 90 cover and the body of the can to an operative position for removing or cutting away the sealed or tagger-tin top of the can, and a handle carried by the cover and movable thereon from an inoperative position within 95 the confines of the same to an operative position with the handle extending beyond the periphery of the cover for being grasped to rotate the same for cutting away the sealed top of the can, the said handle being provided with a portion normally overlying the said cutter and bearing upon the same to hold the same in its inoperative position against accidental displacement. 100

5. In combination, a loose or supplemental cover for hermetically sealed tins or cans, a cutter carried by the cover for removing or cutting away the sealed or tagger-tin top of the can when the cover is rotated on the same, spaced strap portions struck up from the cover, and a handle carried by the cover and slidably movable in said strap portions, the said handle being movable from an inoperative position within the confines of the cover to an operative position with the 110 handle extending or projecting from the periphery of the cover to be grasped for rotating the same. 115

6. In combination, a loose or supplemental cover for hermetically sealed tins or cans, a cutter loosely carried by the cover and radially movable thereon from an inoperative position to an operative position for removing or cutting away the sealed tagger-tin top of the can when the cover is rotated on the same, spaced strap portions struck up from the cover, and a handle carried by the cover and slidably movable in said strap portions, the said handle being movable from an inoperative position within the confines of the 125 cover to an operative position with the 130 handle extending or projecting from the periphery of the cover to be grasped for rotating the same.

cover to an operative position with the handle extending or projecting from the periphery of the cover to be grasped for rotating the same, the said handle being provided at one end with an integral stop co-operating with one of the said strap portions to limit the movement of the handle, the

other end of the handle being provided with a tongue normally overlying the cutter and resiliently keeping the same in its inoperative position. 10

Signed at Baltimore and State of Maryland, this 12th day of July, A. D. 1922.

HENRY HERMANI.
